WRINGER RESET

Nicholas L. Etten, Waterloo, Iowa

Application January 27, 1938, Serial No. 187,167

3 Claims. (Cl. 68—263)

This invention relates to wringer mechanism, and more particularly to a manual wringer release and reset device.

In the conventional wringer construction, a pair of cooperating wringer rolls is held in operative engagement under relatively great spring tension, and is provided with a manual release control and mechanism such that this pressure relationship may be instantly relieved in the event of any emergency.

It is necessary, of course, that means be provided whereby this spring tension may be re-established between the rolls after such release, and to this end most wringers are provided with a manual reset lever which serves to compress the wringer spring and which may then be latched in place until again released by actuation of the manual release control.

The arrangement of parts is usually such that the resetting operation is accomplished by manually moving the release lever from its inoperative to its operative position against the resistance of the tension spring, while the release is accomplished by unlatching this lever and allowing it to fly back to its inoperative or released position.

It is a well recognized fact that this type of construction possesses certain serious disadvantages since the relatively great tension of the wringer spring tends to throw the release lever outwardly with such force and violence as to painfully injure the operator or any other person accidentally struck thereby. In power driven wringers of the modern type these disadvantages are becoming increasingly serious, since the heavy tension springs now in use and the public demand for a wringer that may be easily reset by the ordinary housewife, have resulted in the adoption of comparatively long reset levers in order that a long arc of movement and consequently a high mechanical advantage may be obtained, and these factors of course increase the likelihood of injury by increasing the amplitude of the sweep of the released parts.

Certain attempts have been made to overcome these disadvantages by the provision of retaining links or other auxiliary safety devices, but so far as is known, none of these have been entirely satisfactory.

It is, therefore, a primary object of this invention to provide a wringer of such design and construction as to permit the instantaneous release of the roll pressure without great or violent movement of any external parts.

Another important object of this invention is to provide a wringer including a reset mechanism and a releasable reset handle capable of great leverage during the reset operation and subject to no movement during the release operation. 5

Another object of the invention is to provide a wringer having a release mechanism both sensitive and stable; being of such design that manual release may be accomplished with a minimum effort, but not subject to accidental release. 10

Another object of the invention is to provide a wringer having a movable top housing or hood so mounted that any manual movement thereof will actuate the roll release mechanism, thereby eliminating the necessity of inconvenient and unsightly release bars. 15

A further object is to provide a wringer mechanism including independent resetting links at each end of the rolls, and means for simultaneously releasing and resetting these links. 20

Another object is to provide a release mechanism for wringer rolls, the movement of any parts thereof during the releasing operation being limited to a distance not greater than the movement of the released roll. 25

Another object is to provide a wringer including a release mechanism of simple and rugged construction, not readily subject to damage by rust, dirt, or abuse, and of a nature convenient in use and economical in manufacture. 30

Other objects will appear hereinafter:

Referring now more particularly to the drawings:

Fig. 1 is a longitudinal section through a wringer constructed in accordance with the principles of this invention, the several parts being illustrated in their normal operating position; 35

Fig. 2 is a longitudinal sectional view similar to Fig. 1, the parts being illustrated in the normal released position; 40

Fig. 3 is a longitudinal sectional view similar to Figs. 1 and 2, but showing the parts in their extreme released position; 45

Fig. 4 is a longitudinal sectional view taken substantially along the center line of the wringer;

Fig. 5 is a detailed perspective view of the reset latch;

Fig. 6 is a detailed perspective view of the release latch; 50

Fig. 7 is a plan sectional view taken substantially on the plane of the line 7—7 of Fig. 4;

Fig. 8 is a bottom plan section taken on the line 8—8 of Fig. 3; 55

Fig. 9 is a detailed section through the top mechanism being taken on the line 9—9 of Fig. 3;

Fig. 10 is a detailed perspective view of the release latch trigger;

5 Fig. 11 is a transverse section through the device and taken substantially on the line 11—11 of Fig. 3;

Fig. 12 is a detailed perspective view of one of the top supporting brackets;

10 Fig. 13 is a detail plan section taken on the line 13—13 of Fig. 3;

Fig. 14 is a fragmental longitudinal sectional view showing the several parts in the position they assume during the resetting operation;

15 Fig. 15 is a view similar to Fig. 14, but showing the parts in the position they assume as the resetting operation is completed.

The wringer frame as illustrated in the present embodiment of this invention comprises a lower 20 channel 21 to which is secured a vertically extending outer end channel 22 and a somewhat similar vertically extending inner end channel 23. These channel members are preferably constructed of stamped metal and may be secured to 25 each other in any desirable way, as for example, by means of the spot welding as indicated at 24. A mounting bracket 25 is preferably welded to the inner end channel 23 and is fastened to the power head 26 by means of the machine screws 27 30 in order that the entire wringer structure may be pivotally supported by the drive shaft housing 28 which carries the power head 26. A manual control lever 29 is provided in order to disengage or reverse the driving connections established within 35 in the power head 26 in a manner well known in the art.

In order to facilitate feeding the clothes to the wringer mechanism to be hereinafter described, it is desirable to provide drain boards 31 and 32 40 which are customarily provided with end flanges 33 and which are supported from the wringer frame in any convenient manner, as for example, by means of the drain board brackets 34 and 35. An end casting 36 is secured to a reinforcing 45 plate 37 welded to the outer end channel 22 in order to house the working parts and to improve the appearance of the wringer, and it is also desirable to provide a sheet metal casing 38 which encloses the power head 26 and serves to conceal 50 the mounting bracket 25 and screws 27.

In the normal operation of the machine the upper or driven wringer roll 41 rotates about a stationary axis while the lower or idle wringer roll 42 is so mounted as to permit a certain degree of 55 vertical movement in accordance with the thicknesses of articles being passed between the rolls. To this end the lower roll 42 is mounted on bearing blocks 43 and 44 which are vertically slideable within the outer end channel 22 and the inner end channel 23, respectively. A pair of flanges 45 serve to retain the bearing member 43 within the outer end channel 22 and a somewhat similar pair of flanges 46 retain the bearing member 44 within the inner end channel 23. A tension spring 47 is carried by means of a bracket 48 secured at approximately the mid-point of the lower frame channel 21 and a tension adjusting screw 49 is provided in order that the effective 60 tension of the spring 47 may be varied in accordance with the requirements of the work. The bracket 48 may be secured to the channel member 21 in any desirable way, but it has been found convenient to provide rivets 51 in the side walls of the channel 21 and to provide the bracket 48 with a plurality of notches 52 in such a

manner that the bracket 48 may be supported by the rivets 51.

At each end of the spring 47 a spacer 53 is provided in order that the spring 47 may be effective to urge the lower roll 42 upwardly. Each of the spacers 53 support one of the bearing blocks and each includes a pair of downwardly extending arms 54 joined by means of a cross pin 55 (see Fig. 11) which is carried by one of the ends of the tension spring 47. From the above it should be clear that the lower roll 42 will normally be urged upwardly into engagement with the outer roll 41 by means of the tension spring 47, but as varying thicknesses of material are passed between the rolls, either or both ends of the lower roll may move downwardly against the spring tension.

The upper wringer roll 41, as hereinbefore stated, normally rotates upon a fixed axis, but in case of emergency it may be moved laterally by 20 means of the release mechanism in order to relieve the spring tension effective between the rolls. The release mechanism is also effective to disengage the driving connection between the power head 26 and the rolls, and thus prevent 25 further rotary movement.

At the inner end of the upper roll 41 the roll shaft 61 is journaled in a bearing 62 secured to a bearing slide 63 by means of the rivets 64. The bearing slide 63 includes a downwardly extending 30 skirt portion 65 and a pair of side flanges 66 which preferably do not extend greatly below the lower edge of the bearing 62. It will be seen from an examination of Figs. 4 and 13 that the bearing 62 and bearing slide 66 are vertically slideable 35 within the inner end channel 23 and are retained against outward movement by means of the flanges 66 and against inward movement by means of spacer strips 67 and 68 which serve to divide the space within the channel and thus establish a slideway for the bearing slide 66 and also provide space for accommodating the driving gears. A driven gear 69 is fixedly mounted on the end of the wringer shaft 61 and is adapted to mesh with a driving gear 82 carried by the 40 driving shaft 83 of the power head 26 and thus drive the upper roll 41.

In order to retain the bearing 62 and bearing slide 63 against vertical movement during the normal operation of the machine a pair of links 84 are pivotally mounted on the outer ends of the rivet 85, and these links are secured at their lower ends to a pair of stud bolts 86 carried by a pair of links 87 pivotally mounted on the rivets 88 in the side walls of the inner end channel 23. A sub-top 92 is provided with a pair of downwardly extending arms 92 in order that each of the studs 86 may extend through one of the elongated slots 93 and thus be secured in the position shown in Figs. 1 and 4. By a comparison 50 of Figs. 1, 2 and 3, it will be seen that these linkages may permit a considerable degree of movement of the bearing 62 but that during the normal operation of the machine the pin 85 is seated in the notches 89 in the walls of the inner end 55 channel 23 (see Fig. 3) and at any movement of the links is prevented by the downwardly extending arms 91 of the sub-top 92.

The outer end of the roll 41 is journaled in a bearing 94 secured to the bearing slide 95 by 70 means of the rivets 96, said bearing slide 95 being vertically slideable within the outer end channel 22 and being secured therein by means of the flanges 45. At the upper end of the bearing slide 95 a rivet 96 is provided upon which 75

- are pivoted a pair of links 97 corresponding to the pair of links 84 at the inner end of the machine. A pair of links 98 are pivotally mounted upon ear portions 99 of the outer end channel 22 by means of the rivets 101, and each of the links 98 carries a stud 102 at its free end. These studs 102 correspond to the studs 86 at the inner end of the wringer and serve not only to pivotally connect the links 98 and the links 97 but also extend through the elongated slots 103 in the arm portions 104 of the sub-top 92 and thus prevent any movement of the links 97 and 98 or of the bearing 94 as long as the sub-top 92 is latched in operating position.
- 15 In the operation of the linkages thus described it should be noted that since the rivets 88 and 101 are stationary and that since the rivets 85 and 96 are mounted upon the bearing slides and, therefore, are capable of vertical movement only, any upward force upon the bearing slides due to the action of the spring 47 will tend to cause the links to rotate in a counter-clockwise direction as viewed in the drawings and to move from the position shown in Fig. 1 toward the position shown in Fig. 2. If the sub-top 92 is allowed to follow this movement freely, the bearing slides and the roll 41 may move upwardly; but if the sub-top 92 is latched or otherwise secured in the position shown in Fig. 1, the pairs of studs 86 and 102 will engage the right hand end of the elongated slots 103, and since the motion of these studs is arrested, no vertical movement of the slides will be possible.
- To accomplish this a latch bracket 111 is welded to the inner end channel 23 and is provided with a pivot pin 112 upon which a reset latch 113 may be mounted. This reset latch 113 is preferably of U-shape construction, being provided with a pair of spaced apart side portions 40 114 having perforations 115 through which the pivot pin 112 may extend, and a flange 116 which serves to contact the bracket 111 and thus limit its clockwise pivotal movement. A wire coil spring 17 serves to return the reset latch 45 to its normal position after it has been pivoted in a counter-clockwise direction during the resetting operation.
- A release latch 121 including arm portions 123 is pivotally mounted upon a pivot pin 122 extending between the side walls of the sub-top member 92 and through perforations in each of the arms 123 of the release latch 121. A spring 124 is coiled about the pivot pin 122 and tends to pivot this release latch 121 in a counter-clockwise direction. This movement is limited, however, by means of an upwardly extending stop 125 formed integrally with the release latch 121 and adapted to bear against the end surface 126 of the sub-top 92. When the machine is operating, clockwise pivotal movement of the latch 121 is also prevented by the contact of this stop 125 with the narrow face portion 128 of the retainer block 129 riveted to the lower surface of the release latch trigger 131. This release latch trigger 131 is pivotally mounted upon a stud 132 carried by the sub-top member 92 and is operatively connected with a secondary release trigger 133 pivoted upon the stud 134 by means of a spring connection 135.
- 70 Each of the release triggers 131 and 133 includes a downwardly extending flange 136 having an elongated slot 137 therein adapted to support a pin 138 carrying the spring 135. This spring 135 is effective to urge the flat faces of each of the downwardly extending flanges 136 into engagement and to thus bring the release triggers 131 and 133 into alignment. However, the light force exerted by the spring 135 may be easily overcome and any appreciable lateral force exerted upon either of the release triggers 5 131 or 133 will result in a pivotal movement around the stud 132 in such a manner that the narrow face 132 of the retaining block 129 will disengage the stop portions 125 of the latch 121. The result of this action will be that the force 10 exerted by the wringer spring 47 will be transmitted through the rolls 41 and 42 and through the various linkages and will tend to move the sub-top 92 to the right as shown in the drawings with a sufficient degree of force to overcome the light wire coil spring 124. The latch member 121 will, therefore, pivot in a clockwise direction about the pivot pin 122 and will release the sub-top member 92 from engagement with the reset latch 113. It is obvious that when 20 this occurs the sub-top 92 is free to move in any direction and will no longer act to hold the several linkages against pivotal movement. The result will be that the force of the main spring 47 will be transmitted through the rolls 41 and 25 42 to the several retaining links, which may now freely move from the operating position as shown in Fig. 1 to the normal released position as illustrated in Fig. 2, or, (in the event of there being any bulky object between the rolls) to the extreme released position shown in Fig. 3. The elongated slots 103 in the arms 104 of the sub-top 92 prevent any possibility of a binding action if one bearing slide moves a greater distance than the other.
- 30 It is, of course, necessary that the release may be accomplished very easily by the operator in the event of any emergency and for this reason the present device is provided with a construction such that the entire top housing of the 40 wringer mechanism is movable, and such that any movement of this top housing will result in the instantaneous release of the wringer rolls. By doing this it is not only possible to provide the machine a greatly improved appearance, but it is also an important safety element, since in the event of any emergency it is unnecessary for the operator to strike any control lever or release bar.
- The machine top 141 includes downwardly extending side and end walls 142 which serve to house the internal mechanism, thus not only improving the appearance of the machine but protecting the release mechanism from dirt and water and therefore preventing damage due to 50 rust or corrosion. A pair of top supporting brackets 143 and 144 are welded to the inner surfaces of the side walls 142 by means of the flanges 145 and are provided with turned edges 146 in order to space the brackets 143 and 144 from the 55 sub-top member 92 sufficiently to provide clearance for the free operation of the release triggers 131 and 133. It will be noted that each of these release triggers 131 and 133 carries an anchor stud 148 extending downwardly through an elongated transverse slot 149 in the sub-top 92. A spacer 151 and washer 152 are positioned between the shoulder portion 153 of the stud 148 and the lock nut 154 in order that the stud 148 may be firmly locked to the release trigger 133 70 and yet may be freely movable within the slot 149 in the sub-top 92. This construction allows the anchor studs 148 and the release triggers 131 and 133 to be freely movable within limits sufficient to effect the release of the latch mecha-

nism, but since the anchor studs 148 are locked within the slots 149 in the sub-top 92 any excessive force that might be exerted upon the top cannot damage the relatively delicate release triggers, but will act upon the sub-top 92.

The head portion 155 of each of the anchor studs 148 is adapted to extend upwardly through slots 156 and 157 in the top supporting brackets 143 and 144, respectively, in order that the top 10 141 be supported on the two anchor studs. Each 15 of the slots 156 and 157 includes an enlarged end portion 158 of a size sufficient to clear the head portion 155 of the anchor studs 148 in order that the top assembly may be placed in position after the sub-top and latch release triggers have been 20 assembled. A tension spring 161 extends between the bracket 143 and an ear 162 formed upon the sub-top 92 in order that the top member 141 will be urged to the right as viewed in the drawings, in order to prevent any possibility of 25 allowing the head portions 155 of the anchor studs 148 to accidentally be released from the slots 156. This construction permits the sub-top 92 to continue in its arcuate movement as governed by the pairs of links 87 and 98 even when the path of the top member 141 is obstructed, as by the ears 101 carried by the vertical channel 22, as shown in Fig. 2.

In order to reset the mechanism and to provide 30 an initial tension between the rolls 41 and 42, a resetting shaft 161 is journaled in the mounting bracket 25 and each end of this resetting shaft 161 extends through an opening in the sheet metal casing 38. A resetting handle 163 is secured at 35 each end of the shaft 161 by means of pins 164 in order that the operator may manually rotate the shaft 161 and cause resetting cams 165 affixed to the shaft 161 to engage the sub-top member 92 and thus force the entire wringer mechanism into 40 its normal operating position. By reference to Fig. 13 it will be seen that the downwardly extending arms 91 of the sub-top member 92 include flanges 167 which lie in alignment with and in the path of movement of the resetting cams 165.

45 When the rolls 41 and 42 have been released to their extreme position, the linkages are prevented from moving beyond the position shown in Fig. 3 by means of the stops or flanges 171 on the links 97 and the corresponding flanges 172 on the links 50 84. These flanges 171 and 172 come to bear against the links 98 and 87, respectively, in such a manner that they prevent the linkages from assuming a dead center position and, therefore, the force of gravity will return the upper wringer 55 roll 41 and the entire top mechanism from the extreme position shown in Fig. 3 into the normal released position as illustrated in Fig. 2 and in Fig. 14.

In order to establish a tension between the rolls, 60 however, it is necessary that the upper roll 41 and the entire top mechanism be moved downwardly against the force exerted by the lower roll 42. This is most easily accomplished by simultaneously forcing all of the releasing linkages 65 into position by properly moving the sub-top member 92. The operator may, therefore, rotate either of the reset handles 163 in such a manner as to move the reset shaft 161 in a counter-clockwise direction as viewed in the drawings until the 70 reset cams 165 engage the flanges 167. (See Fig. 14.) By a further rotation through approximately 90° the reset cams 165 will be caused to bear against the flanges 167 and force the sub-top 92 from the normal released position illustrated in Fig. 14 to the normal operating position

illustrated in Fig. 15. This movement will cause the several studs 86 and 102 to be engaged by the ends of the elongated slots 103 and drawn arcuately downwardly, to return all of the release linkages to their normal operating position. 5

As this movement takes place it will be understood that the release latch 121 will not be subject to pivotal movement in either direction since the stop member 125 is locked between the surface 126 of the sub-top 92 and the narrow face 10 128 of the retaining block 129. However, as the hook portions 175 of this release latch 121 engage the reset latch 113, this reset latch 113 may pivot about the pin 112 in a counter-clockwise direction as shown in Fig. 15. As the mechanism 15 reaches the normal operating position the hook portions 175 of the release latch 121 will ride over the reset latch 113, whereupon the wire spring 117 will act to snap the reset latch back into its normal position, thus locking the sub-top 20 member 92 in place.

Since the sub-top member 92 controls all of the several resetting linkages, each of these will be locked in operating position and the operator may, therefore, return the resetting handles 163 25 to their normal idle position, thus releasing the resetting cams 165 from operative engagement with the flanges 167 carried by the sub-top 92.

By this construction it is possible to obtain a great mechanical advantage effective between 30 the reset levers 163 and the main tension spring 47 during the resetting operation and to thereafter disengage these resetting levers during the normal operation in order that they will be subject to no movement at the time that the emergency release mechanism is actuated. This accomplishes an important object, because as hereinbefore pointed out, it is necessary that the wringer be capable of being reset very easily and it is also important that there be no violent 35 movement of any external wringer parts at the time of the release. 40

In this connection it might be pointed out that the extreme vertical movement of any of the external parts is no greater than the actual 45 movement of the roll 41, which is necessary to accomplish the release, and that this movement of the top housing is by no means violent or capable of causing injury to the operator.

By providing a top housing which is bodily 50 movable and which includes downwardly extending flanges housing the release latch, the present structure not only accomplishes important advantages as far as appearance and safety are concerned, but also protects the release latch 55 mechanism against dirt and rust and therefore insures easy operation, combined with sufficient stability to prevent any possibility of accidental release.

While I have shown and described what is at 60 present a preferred form of this invention, it is subject to many variations and modifications without departing from the invention spirit and I, therefore, do not wish to be limited except as by the scope of the appended claims. 65

I claim:

1. In a clothes wringer, a frame, cooperative pressure rolls, resilient means urging said rolls into cooperative engagement, lever link mechanism co-acting between the frame and the rolls 70 for creating roll pressure, a sub frame mounted on said lever link mechanism, a pressure reset handle operable to co-act with said link lever mechanism to create roll pressure, said handle being otherwise independent of said mechanism, 75

releasable latch means to retain said lever mechanism in pressure sustaining position, and a top cover movably mounted on said sub frame co-acting with the releasable latch means whereby 5 horizontal movement of the cover will release the latch means and roll pressure.

2. In a clothes wringer, a frame, cooperative pressure rolls, resilient means urging said rolls into cooperative engagement, link levers connecting the ends of the top roll with the frame, a sub frame link-mounted and connecting said link levers, a pressure reset handle operable to force said link levers into roll pressure position but otherwise separated and independent, 10 releasable latch means to retain lever links in pressure sustaining position and a top cover mounted for universal movement on and over said sub frame, said cover co-acting with said releasable latch means whereby movement of the cover in

a horizontal direction will release the latch means and roll pressure.

3. In a clothes wringer, a frame, cooperative pressure rolls, resilient means urging said rolls into cooperative engagement, link levers connecting the ends of the top roll with the frame, a sub frame linked to and connecting said link levers, means to retain extension of said links to less than straight line position, a pressure reset handle operable to force said links into 10 roll pressure position but otherwise separated and independent, releasable latch means to retain lever links in pressure sustaining position, and means to release said latch means and roll pressure, said release of roll pressure being accompanied by only limited vertical movement of the top roll and attached mechanism as constrained by the link levers. 15

NICHOLAS L. ETSEN.
